G. A. WATKINS, OF PROCTORSVILLE, VERMONT.

Letters Patent No. 76,569, dated April 7, 1868.

IMPROVED CHAIR-SEAT.

The Schedule referred to in these Letters Patent and making part of the same.

TO ALL WHOM IT MAY CONCERN:

Be it known that I, G. A. WATKINS, of Proctorsville, in the county of Windsor, and State of Vermont, have invented a new and useful Improvement in Chair-Seats; and I do hereby declare that the following is a full, clear, and exact description thereof, which will enable others skilled in the art to make and use the same, reference being had to the accompanying drawings and to the letters of reference marked thereon.

This invention relates to a new and improved mode of securing bottoms in the seat-frames of chairs, and is more especially designed for the securing of the ordinary cane-bottoms in the seat-frames.

At present the cane is woven by hand in the seat-frame at considerable labor and expense, the strips of cane being passed through holes in the seat-frame.

By my improvement the cane may be woven in a loom constructed for that purpose, the woven cane cut into pieces of suitable dimensions, according to the size of the seat-frames, and secured thereto with the greatest facility.

Wire-cloth and other material used for bottoms may also be secured in the seat-frames by the same means. In the accompanying sheet of drawings—

Figure 1 is a plan or top view of a portion of a seat-frame, having a cane seat secured to it according to my invention.

Figure 2, a section of the same, taken in the line $x x$, fig. 1.

Similar letters of reference indicate like parts.

A represents a portion of the seat-frame of a chair, which may be constructed in the usual way. The top of this frame has a groove, a , made in it all around to receive strips B, a strip being in each rail b of the seat-frame, the abutting-ends of the strips being bevelled to form mitre-joints, c , as shown in fig. 1.

The bottom, C, after being cut of the proper size, has its edges bent down into the grooves a , and the strips B are then inserted in the grooves, and drawn down therein, and secured by screws d , the latter passing up through the bottom of the rails b into the strips B, as shown clearly in fig. 2.

By this simple means the bottom will be held firmly in position, and in case of a bottom becoming injured or broken, a new one can be applied without any difficulty whatever, and by any person of ordinary ability, the services of a mechanic not being required for that purpose.

Having thus described my invention, I claim as new, and desire to secure by Letters Patent—

The securing of bottoms in chairs by having grooves a made in the upper surface of each rail b of the seat-frame, and having strips B to fit in said grooves to clamp and firmly hold the edges of the bottom in the grooves, the strips being drawn into the grooves, and firmly secured in position by screws d or other means, substantially as set forth.

G. A. WATKINS.
